US00D783887S

(12) **United States Design Patent** (10) **Patent No.:** **US D783,887 S**
Stanley (45) **Date of Patent:** **** Apr. 11, 2017**

(54) **HORTICULTURE GROW LIGHT**

(71) Applicant: **IP Holdings, LLC**, Vancouver, WA (US)

(72) Inventor: **John Stanley**, Vancouver, WA (US)

(73) Assignee: **IP Holdings, LLC**, Vancouver, WA (US)

(**) Term: **15 Years**

(21) Appl. No.: **29/552,185**

(22) Filed: **Jan. 20, 2016**

Related U.S. Application Data

(63) Continuation of application No. 29/511,535, filed on Dec. 11, 2014, now Pat. No. Des. 751,245.

CLAIM

The ornamental design for a horticulture grow light, as shown and described.

DESCRIPTION

FIG. 1 is a perspective view a horticulture grow light, as viewed from below, showing my new design;

FIG. 2 is a perspective view of the grow light shown in FIG. 1, as viewed from above;

FIG. 3 is a left side view of the light shown in FIG. 1; FIG. 4 is a right side view of the light shown in FIG. 1; FIG. 5 is a front elevation view of the light shown in FIG. 1;

FIG. 6 is a rear elevation view of the light shown in FIG. 1; FIG. 7 is a top plan view of the light shown in FIG. 1; and, FIG. 8 is a bottom plan view of the light shown in FIG. 1. The broken-line disclosure shown in the views is understood to represent portions of the article in which the claimed design is embodied, but which form no part of the claimed design.

1 Claim, 6 Drawing Sheets
